(57) **CLAIM**

The ornamental design for a gripper for robot as shown and described.

DESCRIPTION

FIG. 1 is a perspective view of a gripper for robot showing our new design;

FIG. 2 is a front view thereof; a rear view being a mirror image;

FIG. 3 is a right side view thereof; a left side view being a mirror image;

FIG. 4 is a top view thereof;

FIG. 5 is a bottom view thereof; and,

FIG. 6 is a reference view thereof showing the gripper for robot in use state.

The broken lines shown in FIG. 6 are for the purpose of illustrating environmental structure and form no part of the claimed design.

1 Claim, 6 Drawing Sheets
